UNITED STATES PATENT OFFICE.

JAMES E. FOULKS, OF BRIGHTWATERS, NEW YORK, ASSIGNOR TO CLIMAX STATIONERY COMPANY, INC., OF NEW YORK, N. Y., A CORPORATION OF NEW YORK.

BINDING OF PERFORATED LOOSE SHEETS.

Application filed September 29, 1926. Serial No. 138,373.

This invention relates to the binding of perforated loose sheets between a pair of cover sections having perforations to register with the perforations in the sheets for the engagement of fasteners, and it is the object of the invention to provide improved binding means comprising a strip of pliable and readily severable metal folded upon itself to form a head at the fold with two parallelly extending portions or tongues the free ends of which are arranged to extend beyond one of the covers, and to provide locking means to engage the free ends of the strips comprising a blank of pliable metal arranged to be engaged upon and interfolded with the free ends of the fasteners.

Another object of the invention is to provide a fastener or binder of pliable and readily severable material to adapt the fastener for the binding of stacks of sheets of variable thicknesses.

In the drawing accompanying and forming a part of this specification Figure 1 is a perspective view showing a number of loose sheets as bound between two cover members with one of the cover members in open position and broken away, and showing an embodiment of my improved binding means in binding position.

Figure 2 is a fragmentary view in perspective of a sheet to show an arrangement of perforating the same.

Figure 3 is a cross sectional view of a stack of sheets and cover members to be bound taken on the line 3—3 of Figure 1 and showing the binding means in relation thereto.

Figure 4 is a cross sectional view taken on the line 4—4 of Figure 3 looking in the direction of the arrow.

Figure 5 is a perspective view of one of the fastener or binder members.

Figure 6 is a perspective view of the means for locking the sheets upon the binder members shown in Figure 5.

Figures 7 to 10 are a series of views in perspective showing the successive steps in interlocking the fastener and locking means.

Figure 11 is a perspective view showing the final step of interlocking the fastener and locking means.

Figure 12 is a perspective view of a modified form of binder showing the cover members movably connected to a back and hinged carrying the locking means.

Figure 13 is a perspective view of a portion of a cover member showing a form of hinge member mounted thereon in the arrangement of binder shown in Figure 12 to movably connect the locking means thereto. 60

Figure 14 is a perspective view of a stack of sheets showing the locking means utilized in the embodiment shown in Figure 12 in relation thereto, and

Figure 15 is a perspective view of the locking member shown in Figure 12 for the engagement of the fastener or binder shown in Figure 5.

Figure 16 is a perspective view of a perforated hinge plate with the binder inserted. 70

In the embodiment of the invention a stack of sheets having perforations 17 adjacent one of the side edges and having a slit 18 communicating therewith cut through the edge of the sheet are bounded by a pair 75 of cover members 19, 20 having a strip flexibly connected thereto at one edge, as at 21, to lie contiguous to the inner surface of the sheets over which the cover members are adapted to be folded and to act as a hinge 80 for said covers. The strips 21 are arranged with perforations 22 spaced to register with the sheet perforations. The cover members are placed at the top and bottom of a stack 85 of sheets with the perforations of the hinge strip placed in register with the perforations in the sheets. Fasteners are then passed through the perforations, comprising a strip of flat laterally pliable edgewise stiff and readily severable metal bent upon itself 90 in such a manner, as shown in Figure 5, to form a head 23 adapted to abut against the hinge strip of a cover, the lower cover 20 in the present instance, and parallelly extending portions or tongues 24 with the free ends thereof extending beyond the hinge strip 21 of the upper cover 19 when the cover is in open position as shown in Figures 3 and 4. The fasteners are engaged in the perforations of the sheet body with the width thereof to extend parallel to the edge of the sheets whereby the fasteners, due to the flexibility of the metal, will readily adapt themselves to conform to the curvature of the sheets as the bound sheets are spread in the open condition thereof. A

plate 25 of pliable material having greater length than breadth is provided with a perforation 26 arranged lengthwise of the plate and corresponding in shape with and of a 105 110 115

size substantially the same as the cross sectional area of the tongues 24 of the fastener and with the ends 27, 27' reduced in width and bent at right angles to the body portion of the plate. This plate is engaged over the free ends of the fastener as shown in Figures 3 and 4. It will be noted that the free ends of the fasteners may be of a length to extend for some length above the plates 25 whereby they are adapted to the binding of stacks of sheets or sheet body of different thicknesses. In the arrangement as shown in Figures 3 and 4 with the free ends extended for a considerable length above the sheets a predetermined portion is severed therefrom, as on the dotted line 24^a (Figure 3), this length depending upon the width of the tongues of the fasteners and the length of the plates 25 between the angle portions 27, 27'. The fasteners as stated are made of thin and severable metal, such as brass, which may be readily cut by a pair of shears. The plate 25 is then engaged upon said projecting end of the fastener as shown in Figure 7, or it may be engaged thereon before the fastener is severed, when the free ends of the fastener tongues are spread and bent flat against the plate between the bent ends 27, 27' as shown at 24^b in Figure 8. One of the ends of the plate 25, such as 27, is then bent over and against the surface of the spread fastener ends as shown in Figure 9. One of the spread fastener ends 24^b is then bent backwards upon itself over the bent end 27 of plate 25, as shown at 24^c in Figure 10, when the other end 24^b is bent backwards upon itself over the bent end 24^c. The plate end 27' is then bent over the interfolded ends as shown in Figure 11 when the same may be struck with an implement, such as a hammer, to flatten the same.

In the modified form of binder shown in Figures 12 to 16 the two covers 19, 20 are pivotally or hingedly connected to a back 28 by arranging spaced rolled portions 29, in the nature of hinge knuckles, along the opposite longitudinal edges of the back for the engagement of a pintle wire 30. The covers 50 have hinged members 31 mounted along an edge arranged to engage the spaces between the knuckles 29 of a length less than said spaces to be engaged by the pintle wire 30. The sheets are bound by means of the binders or fasteners 24, and to unite the cover with the sheets perforated plates 32 (Figure 16) are provided, these plates being arranged with an eye or knuckle 33 for engagement on one of the pintles 30 in juxtaposed relation to the hinge member 31 to lie contiguous to and have movement on the pintle independent of a cover member, in the present instance the cover member 20. The plates are arranged in interposed relation between a cover member and a stack

of sheets engaged between the covers with the perforations therein in registration with a perforation in the stack of sheets, the binder or fastener 24 being passed through the plate perforation with the head 23 in 70 abutting relation thereto. Securing plates 25' (Figure 15) are provided similar to the plates 25 with the exception that they are formed with an eye or knuckle 34 at one longitudinal edge whereby they are mounted upon the pintle wire 30 for connecting the other cover member 19 to the back to have movement on the pintle independent of the cover member. These plates are arranged to lie contiguous to the inner surface of the 80 cover 19 in interposed relation to said cover and the upper surface of the stack of sheets, as shown in dotted lines in Figure 12. The plates have a perforation 26' for the passage of the ends of the tongue portions of 85 the fasteners extending beyond the top of the stack of sheets and extended portions 27^a, 27^b for interfolding with the ends of the fastener tongues in a manner similar to that described in connection with Figures 90 7 to 11. It will be obvious that by this arrangement a flat opening back arrangement of binder is provided and adapted for use as a check book, order book and the like by the binding of blank checks or order blanks 95 between the cover members 19, 20.

Having thus described my invention, I claim:

1. In means for binding perforated loose sheets into a sheet body, a strip of pliable and readily severable metal folded upon itself with the folded portions to extend in parallel relation and arranged at the fold with an abutment, said strip being adapted to be engaged in the sheet perforations with 100 the abutment contiguous to one side of the sheet body and the free ends extending beyond the opposite side of the sheet body, and a plate of pliable metal of greater length 105 than width with the opposite ends arranged with perpendicular flap portions and having a perforation, said plate being engaged over the free ends of the strip in abutting relation to the outer sheet of the sheet body, and then severing the ends of the strip to 110 predetermined length and interfolding the ends of the strip with the flap portions of the plate.

2. In the binding of perforated loose sheets into a sheet body, a flat strip of laterally pliable and edgewise stiff material arranged with a head at one end engaged in the sheet perforations with the width of the strip extending parallel to the binding edge 120 of the sheets and the head abutting a marginal portion of the opening at one side of the sheet body and the free end extending through perforations beyond the opposite side of the sheet body, and a pliable metal 125 perforated plate engaged upon the free end 130

of the strip and the plate and free end of the strip and plate interfolded upon each other to lock the strip in sheet binding position.

5. 3. Means for the binding of perforated sheets into a sheet body, comprising a flat strip of laterally pliable and edgewise stiff and readily severable metal folded upon itself with the ends to extend in parallel relation and arranged at the fold with an abutment, said strip being engaged in the perforations of the sheets with the width of the strip extending parallel to the binding edge of the sheets, and a perforated plate 10 of pliable material engaged upon the free ends of the strip and interfolded with the end portions of the strip.

4. In means for binding perforated loose sheets into a sheet body, a strip of pliable material folded upon itself and arranged at the fold with an abutment engaged in the 15 perforations of the sheets with the width

of the strip extending parallel to the binding edge of the sheets with a perforated plate engaged on and interposed between the abutment and sheet body, and a perforated plate arranged at the ends with flap portions engaged upon the free ends of the strip and the flap portions interfolded with the end portions of the strip, said perforated plates 20 being arranged with an eye at a marginal portion.

5. Means for binding perforated loose sheets into a sheet body as claimed in claim 1, wherein the free ends of the strip are spread in contiguous and opposed position to the plate arranged with the flaps, and the free ends of the strip and the flap portions of the plate are successively interfolded one upon the other.

Signed at the city of New York in the county of New York and State of New York this 25th day of September, 1926.

JAMES E. FOULKS.
